HARLEY J. SCHOON

By *Wing. A. McCathran*

HIS ATTY.

10 will then pour out through the opening 12 and fall into the upper open end of the sack S. It should be noted that the transverse stop bar 36 will swing under the bottom of the spout 11 and contact the bottom of the basket 10 and limit the swing of the arms 23 in a downward direction and support the bag or sack-supporting means in a rigid open position. The arms 24 extend substantially horizontally when the sack-supporting means are swung to an operative extended position.

It will be noted that an efficient means is provided to firmly hold the sack-supporting means in a folded or inoperative position, when not in use, as well as providing means to firmly brace the sack-supporting means when the arms 23 are swung to an operative or open position.

Having described the invention, what is claimed as new is:

In combination with a receptacle having a discharge opening, a discharge spout adjacent the opening, a sack-supporting means movable to and from an operative position, said sack-supporting means comprising a plurality of spaced arms pivoted to said spout and having a transverse connecting stop bar at their rear ends, said

5 stop bar being adapted to swing under said spout and contact the bottom of said receptacle to limit the outward swing of the arms and hold the arms in an operative and substantially horizontal position, sack-engaging hooks carried at the opposite ends of said arms for suspending a sack below said spout and discharge opening, and spring tongues carried by said spout for engaging said arms when said sack-supporting means is swung to an inoperative position to hold the sack-supporting means in a locked inoperative position.

HARLEY J. SCHOON.
